CHAUNCY O. CROSBY, OF NEW HAVEN, CONNECTICUT.

Letters Patent No. 105,313, dated July 12, 1870.

IMPROVEMENT IN MACHINES FOR PAPERING NEEDLES.

The Schedule referred to in these Letters Patent and making part of the same

To all whom it may concern:

Be it known that I, CHAUNCY O. CROSBY, of New Haven, in the county of New Haven and State of Connecticut, have invented a new Improvement in Machine for Papering Needles; and I do hereby declare the following, when taken in connection with the accompanying drawings and the letters of reference marked thereon, to be a full, clear, and exact description of the same, and which said drawings constitute part of this specification, and represent in—

Figure 1, a side view;

Figure 2, a front view, the feeding-rolls removed; and in

Figure 4 to inclusive, detached views to illustrate the construction and operation of the machine.

This invention relates to a machine for arranging sewing-needles, the object of which is to place the requisite number of needles into proper position in a piece of fabricated material preparatory to papering; and consists in an automatic device, which delivers from the hopper the requisite quantity of needles, presents them in a position parallel to each other, forces them so arranged into a fabricated material, and delivers the needles thus arranged and stuck, from the machine, in a condition to be placed in papers.

To enable others to construct and use my improvement, I will fully describe the same as illustrated in the accompanying drawings.

Before proceeding to a full description of the machine, I will describe the arrangement of the needles as they come from the machine, as shown in figs. 12, 13, and 14.

1 is a strip of fabricated material through which the needles are inserted, so that the center portion of the needles are upon one side of the fabric, as seen in fig. 13, while the points and edges are upon the other, and between the center portion of the needles and fabric is placed a strip of paper, 2, denoted in blue, fig. 14, the fabric in red, the needle in black. The fabric is cut so as to separate each set of needles; then the paper folded back over the central portion of the needles, as seen in fig. 15, by means of which strip of paper the needles are gummed or secured to another strip of paper which incloses the needles entire.

A is the bed-plate, supporting in bearings B a driving-shaft, C, caused to revolve by the application of power thereto in any convenient manner.

D is a hopper, arranged so as to receive a quantity of needles, the needles placed therein the points all in one direction.

In a machine constructed as in the drawing, the points are from the driving-shaft.

Beneath the hopper are arranged two guides, *a a*, which said guides are respectively operated through levers *A¹*, by cams *A²* on the driving-shaft, and above

the said guides, at the mouth of the hopper, is arranged a slide or cut-off, *d*, operated through a lever, *B¹*, by a cam, *B²*.

The said guides approach each other only so near, as seen in fig. 4, as to permit the needles to pass freely from the hopper into the space between the two, yet the space so narrow that the needles are all kept in line one above the other.

The cut-off *d* is arranged so as to cut off the column of needles when the requisite number has passed between the guides *a*; that is, as seen in fig. 4. The cut-off opens from the column of needles to the guide, to permit the passage of the needles between the guides. Then the cut-off is forced in over the guides, to cut off the column, as seen in fig. 5, holding the column above the cut-off. When the column is thus cut off, as in fig. 5, the follower *b* advances, the rear of the guides being open, so as to permit the follower to pass a little way in between the guides, as seen in fig. 5, and force the needles forward from the guides, as denoted in red, fig. 5.

The points of the needles, in moving this short distance, enter the fabric, as more fully hereafter described, thus sustaining and guiding the points while the eyes or heads are held in the follower by a groove formed in the end of the follower for that purpose, as seen in fig. 4; then, when the points and heads are thus held, the guides open, as seen in fig. 6, and permit the follower *b* to pass between and force the needles into the fabric; then the follower returns, the guides close, and the operation is repeated.

The fabric upon which the needles are stuck is arranged upon a spool, *E*, or in any convenient position for conduct from the machine.

The strip of paper is arranged upon a spool, *M*, or in any convenient position for conduct into the machine over a guide, *M'*.

Upon a vertical slide, *H*, is arranged a guide, *i*, seen in fig. 11, the said slide operated by means of a cam, *I*, through a lever, *I'*, the said guide *i* being arranged so that, when it is raised to the position in fig. 16, it will be in such relative position to the follower and the needles between the jaws *a a* that the needles will pass to one side of the said guide *i*, here represented as the left-hand side, the guide itself being as thin as conveniently may be.

Upon the frame in front of the guides *a* is arranged a slide, *L*, operated by a cam, *F²*, through a lever, *F³*, so as to move transversely in a line at right angles to the path of the needles in their passage from the machine.

Upon the said slide *L* are arranged two wings, *f*, one upon either side, as seen in fig. 9, the distance between the two being such as to allow the free passage of the guide *i* up and down between the two, and opposite the said wings is arranged a corresponding slide;

L^1 , operated by a cam, L^1 , through a lever, L^2 , so that, when the said wings f are forced across to meet the said slide L^1 , as seen in fig. 10, the two together form a clamp, for the purpose more fully hereafter described.

The fabric, running from the spool E , passes through a jaw, F , which is arranged so that, by the action of the cam F^1 , it will grasp the fabric, receiving from the said cam a reciprocating movement, and advance toward the machine, carrying with it the requisite quantity, as shown by the two positions in fig. 9.

The fabric is passed into the machine and grasped between the wings f and slide L^1 , as seen in fig. 10, and thence is carried to the feeding-rolls G , which are in constant revolution, operating so as to draw the fabric from the machine when free.

While the fabric is held as in fig. 10, the slide H rises, carrying the guide i between the wings f , back of the fabric.

Upon the said slide H is arranged a lever, l , which, when the slide H is down, is turned to the position denoted in red, fig. 11, so that, when the slide ascends, as from the position in fig. 11 to that in fig. 16, the said lever will pass up upon the opposite side of the fabric to the guide i , and, when it has thus passed up, an arm, t , of the lever l , strikes a pin, n , on the frame of the machine, which turns the said lever into the position denoted in fig. 16. At the same time the wings f are withdrawn, and the lever l draws the fabric around the guide i , as seen in fig. 9, leaving a space between the guide and the edge of the wings f , so that the needles, when they are forced forward, as before described, will enter the fabric and pass through the back of the guide i , so as to inclose the guide between the needles and the fabric. The guide i is then drawn down by the slide H , and with it the lever l ; then the jaw F advances, delivering more fabric, and that portion of the fabric in which the needles have been stuck being free, is, by the revolution of the feeding-rolls G , drawn from the machine; then the wings f grasp the fabric against the slide L^1 , as before, the jaw F returns and grasps the fabric in the rear, the guide i , with the lever l , again rises, a second series of needles is delivered and stuck as before, and so on.

To attach the paper during the operation which I have just described, I arrange a slide, N , operated through a lever, N^1 , by a cam, N^2 .

On the said slide N is arranged a jaw, r , and a corresponding hinged jaw, s , (see figs. 7 and 8,) the said hinged jaw operated to open, to receive the paper through a lever, s^1 , operated by a cam, s^2 , bearing upon a lever, s^3 , fixed to the movable jaw, as seen in fig. 7.

In this position a strip of paper, denoted in blue, passing through the guide M' , is delivered into the said jaws, so that, when the said jaws descend, they carry with them the strip of paper, so as to carry the paper down between the fabric and the guide i .

On the slide L , and moving with it, I arrange a cutter, t , and upon the slide L^1 a corresponding cutter, t' , the two cutters acting as a shear, so that, after the paper has thus been drawn down and the wings f advance to close upon the fabric, the said cutters will cut from the strip of paper the length required. Thus cut, the paper is held by the jaws until the fabric is drawn back to the position in fig. 9, which binds the paper between the guide i and the fabric; therefore, when the needles are stuck into the fabric, as before described, and the guide withdrawn, the paper is held between the needles and fabric, as denoted in fig. 12, and in this position the fabric, with the needles and paper, is drawn from the machine; then the fabric is cut and the paper folded, as before described.

I have represented the needles as delivered and stuck in a position one above the other, the fabric passing into the machine upon its edge. The position of the parts is not essential, as the needles may be delivered in any other position, and in substantially the same manner inserted into the fabric.

Having fully described my invention,

What I claim as new and useful, and desire to secure by Letters Patent, is—

1. The cut-off d , in combination with the hopper D , jaws a , and the follower b , arranged so as to operate substantially in the manner set forth.
2. The gripping device r and slide N , in combination with guide M' and cutters t t' , substantially as described.
3. The combination of the slide L with its wings f , slide L^1 , and guide i , substantially as described.
4. The combination of the slide L with its wings f , slide L^1 , guide i , and lever l , operating together substantially as set forth.
5. The slide L , with its wings f , slide L^1 and guide i , combined with the feeding device F , substantially as described.
6. In combination with the subject-matter of fifth clause, the take-up rolls G , operating substantially as specified.

C. O. CROSBY.
